UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

POSITIONING DEVICE FOR CAR COUPLERS.

Application filed June 16, 1926. Serial No. 116,408.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range."

It is very often necessary to couple cars on curves and frequently with the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the number of broken knuckles and guard arms on couplers which members are frequently

bent or broken when the couplers are not within coupling range. Such devices also reduce the number of accidents to trainmen as they are not required to go between the cars and position the coupler preparatory to coupling.

A common form of car coupler positioning device comprises a coupler carrier swingably suspended by links from some part of the car so that the objects and advantages mentioned above are obtained and my invention is an improvement upon such devices and consists in providing a shiftable bearing construction to increase the eccentricity of the weight of the coupler (and its associated parts) about its point of support, thus increasing the resultant force tending to return the coupler to the longitudinal center of the car (or away therefrom when the car is tipped.) I accomplish this result without necessarily increasing the vertical rise of the coupler. This is important because the A. R. A. standard dimension only permits $\frac{3}{4}$ " vertical rise of the coupler.

In my device the coupler carrier is swingably suspended from any convenient part of the car by a link at each of its ends and is provided with means such as lugs to prevent lateral movement of the coupler relative thereto. At least one of these links has spaced apart portions both supporting the link (and its load) when it is in its normal central position. When the carrier swings in one direction, one of the portions moves away from its support, thus shifting the load upon that link entirely to the other portion. A similar action takes place when the carrier swings in the opposite direction. It is preferable that the carrier maintain a horizontal position at all times, which is accomplished by arranging the links so that a vertical line passing through the pivot connection of the link bisects the distance between the spaced apart portions of the link. When the shiftable bearing construction is used at both ends of a link, the parts are arranged so that a vertical line bisects the distances between the pairs of spaced apart elements.

The shiftable bearing construction may be used on one or both ends of one or both links. It may be used to function on one link when the carrier moves in one direction and upon the other link when the carrier moves in the other direction, or it may be

applied to one end of one link to function when the link swings in either direction. Furthermore, the shiftable bearing construction may be arranged with contacting 5 points or lines between the link and car part or between the link and the carrier, but a journalized bearing is preferable to provide greater bearing area. In a journalized arrangement, the journal may be on the car 10 part and the journal bearing on the link or vice versa, or in fact, the link may have a journal and a journal bearing engaging a journal bearing and journal, respectively, on the car part.

15 In the drawings:

Fig. 1 shows a typical application of my device to a railway car.

Fig. 2 is a section on line 2—2 of Fig. 1.

Fig. 3 is a side elevation of Fig. 1.

20 Figs. 4 and 5 are skeleton diagrams showing the device, respectively in normal position and with the carrier moved laterally.

Fig. 6 is a detail of the carrier.

Fig. 7 is a detail of the link.

25 Figs. 8 and 9 show modified forms of the link.

Fig. 10 is a section on line 10—10 of Fig. 9.

30 Figs. 11 and 12 are skeleton diagrams showing a modified form of the device, respectively when the carrier is in normal position and with the carrier moved laterally.

Fig. 13 is a detail of the link shown in 35 Figs. 11 and 12.

Figs. 14 and 15 show modified forms of the link shown in Fig. 13.

In the arrangement shown in Figs. 1—10, inclusive, the double bearing construction is 40 used at the lower ends of the links and the upper ends of the links are pivoted at a part of the car. A journalized construction is shown. When the coupler 2 is in its normal central portion (as shown in Fig. 1) the journal bearing 3 on the carrier 4 engages the journal 5 on the link 6 and at the same time the journal bearing 7 on the link engages the journal 8 on the carrier. When the coupler moves distance "A" to the right 45 (as shown in Fig. 5) the journal bearing 3 on the right end of the carrier moves away from the journal 5 on the link so that the right end of the carrier is entirely supported by the journal 8 of the carrier resting upon the journal bearing 7 of the link.

The eccentricity or lever arm of the load on this link is the horizontal distance "C" 50 between parallel vertical planes 10—11 passing, respectively, through the upper pivot 12 and the contact line between the journal 8 on the carrier and the journal bearing 7 on the link. At the same time the journal 13 on the left end of the carrier moves away from the journal bearing 14 on the link so 55 that the left end of the carrier is entirely

supported by the journal bearing 15 of the carrier resting upon the journal 16 of the link. The eccentricity of the load on this link is the horizontal distance "B" between parallel vertical planes 17—18, one of which 70 passes through the upper pivot 19 and the other of which passes through the contact line between the journal bearing 15 of the carrier and the journal 16 of the link. There is no eccentricity when the device is 75 in normal position because a vertical plane 30 passing through the upper pivot 12 passes between the two contacting lines 3—5 and 7—8 of the connection between the link and the carrier. Of course, the 80 link could be reversed and still obtain the desired results, i. e., the carrier could be pivoted to the link and the double bearing construction used between the link and the car part.

85 In the usual centering device link, which is pivoted at both ends, the eccentricity of the load upon the link is equal to lateral swing (A) of the carrier, but in my arrangement this eccentricity is increased by one-half the distance between the spaced apart bearings. In other words, when the carrier moves distance "A" (Fig. 5) both "B" and "C" are greater than "A".

This shifting of the bearing moves the 95 center of the effective radius of the link and the parts may be so proportioned as to maintain the same radius or to increase or decrease it, as desired. In any event, however, the eccentricity of the load about its support 100 is increased. Decreasing the effective radius increases the vertical rise of the carrier in a given amount of lateral movement, while increasing the effective radius decreases the said rise. The effective radii of the right 105 and left link, respectively, are shown at "D" and "E" in Fig. 5.

Fig. 6 shows the carrier of the form shown in Figs. 1—5 inclusive. The semi-cylindrical projections form the journals 8—13 and the 110 semi-cylindrical depressions 3—15 form the journal bearings.

Fig. 7 shows the link 6 of Figs. 1—5 inclusive in detail. The upper hook 21 engages the pivot 12 and the lower hook 22 forms 115 the double bearing construction wherein the inside of the hook forms the journal bearing 7 and its end is rounded to form a journal 5.

When the link is made from a metallic bar it may be strengthened and stiffened by 120 an integral rib or corrugation 23 which extends through the major part of the hook and terminates (24) within the bar so as not to interfere with the journal. If a hook is 125 merely used to engage a pivot the rib may extend through the entire hook. This corrugation also reinforces the shank 25 when possible, as shown in Fig. 9. Fig. 10 shows the rib.

Fig. 8 shows another form of the link de- 130

signed for a pivoted connection at one end wherein an eye is used instead of a pivot hook.

Fig. 4 shows the device when the coupler is in normal position and Fig. 5 shows the device with the coupler moved laterally. In these figures the immaterial parts of the car have been omitted.

Figs. 11-14 inclusive show a modification wherein the double bearing construction is used on both ends of the links 39. The action at the bottom of the link is the same as heretofore described, and a similar action takes place at the top of the link. When the carrier moves a distance "F" (Fig. 13) to the right the journal bearing 31 on the upper end of the right link leaves the journal 32 on the car part (33) thus shifting the entire load on this link to its upper journal 34 which is supported by the journal bearing 35 on the car part. At the same time, the journal 36 on the upper end of the left link leaves the journal bearing 37 on the car part 33, thus shifting the entire load on the left link to its journal bearing 38 which is supported by the journal 49 on the car part.

The eccentricity of the load on the link is the horizontal distance between parallel vertical planes, one of which (40) passes through the contact line of the car part and the link and the other of which (41) passes through the contact line of the link and the carrier. In the usual centering device link, which is pivoted at both ends, the eccentricity of the load upon the link is equal to the lateral swing "F" of the carrier, but with this twofold double bearing arrangement the eccentricity is increased by half the distance between each pair of spaced apart bearings. In other words, when the carrier moves a distance "F" (Fig. 12) both "G" and "H" are greater than "F". There is no eccentricity when the device is in normal position because a vertical plane 42 passes between the upper spaced apart portions 31-32 and 34-35 and also passes between the lower spaced apart portions 3-5 and 7-8.

Fig. 13 shows the link 39 of the form shown in Figs. 11 and 12. Figs. 14 and 15 show a link 43 and 44 with the hook ends bent in opposite directions. In Fig. 15 a vertical plane (45) passes through the opposite journal bearings 46-47, while in Fig. 14, a vertical plane (48) passes midway between the journal and journal bearing at each end of the link, or broadly speaking, between the spaced apart portions.

There are certain advantages to be obtained by arranging the spaced apart portions of the link so that one of them is out of contact when the coupler is in normal position, but which functions after a predetermined amount of swing of the link. Such a construction is covered by application for patent, Serial No. 116,406, filed June 16, 1926.

In the device covered by this application the load is shifted from one bearing to another by the lateral movement of the carrier. There are certain advantages in having a gradual shifting of the bearing which are accomplished by a rolling engagement between the link and the car part (or carrier) which is covered by application for patent, Serial No. 116,407, filed June 16, 1926.

The drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car; the combination of a car part element, a coupler carrier element, one of said elements provided with a journal and journal bearing, and a pair of links swingably suspending the carrier to the car part, one of said links having a journal bearing and a journal at one end engaging the journal and journal bearing on said element when in normal position.

2. In a railway car; the combination of a car part element, a coupler carrier element, one of said elements provided with a journal and journal bearing, and a pair of links swingably suspending the carrier to the car part, one of said links having a journal bearing and a journal at one end engaging the journal and journal bearing on said element when in normal position, the journal on the element moving out of engagement with the journal bearing on the link when the carrier swings in one direction and the journal on the link moving out of engagement with the journal bearing on the element when the carrier swings in the opposite direction.

3. In a railway car; the combination of a car part element, a coupler carrier element, one of said elements provided with a journal and journal bearing, and a pair of links swingably suspending the carrier to the car part, one of said links having a journal bearing and a journal at one end engaging the journal and journal bearing on said element when in normal position, one of said journals moving out of engagement with its journal bearing when the carriage moves in either direction.

4. In a railway car; the combination of a car part, a coupler carrier with a journal and a journal bearing adjacent each of its ends, and a pair of links swingably suspending the carrier to the car part, said links each having a journal bearing and a journal at its lower end engaging, respectively, the journals and journal bearings of the carrier when in normal position.

5. In a railway car; the combination of a car part, a coupler carrier with a journal

and a journal bearing adjacent each of its ends, and a pair of links swingably suspending the carrier to the car part, said links each having a journal bearing and a journal at its lower end engaging, respectively, the journals and journal bearings of the carrier when in normal position, one of the journals on the carrier moving out of engagement with its link and one of the journal bearings of the carrier moving out of engagement with the other link when the carrier swings in one direction and vice versa when the carrier swings in the opposite direction.

15. 6. In a railway car; the combination of a coupler carrier having a semi-cylindrical projection at one end forming a journal and a semi-cylindrical depression adjacent said journal forming a journal bearing, and a link swingably suspending the carrier to the car, said link having a hook at its lower end forming a journal bearing for the journal of the carrier with the end of the link rounded to form a journal for the journal bearing of the carrier.

7. As an article of manufacture, a link for a car coupler positioning device having a shank with a hook at one end forming a journal bearing with the end rounded to 30 form a journal.

8. As an article of manufacture, a link for a car coupler positioning device having a shank with a hook at each end forming a journal bearing with each end rounded to 35 form a journal.

9. As an article of manufacture, a link for a car coupler positioning device made of metallic bar comprising a shank with a hook at one end forming a journal bearing 40 with the end rounded to form a journal, said bar reinforced by an integral corrugation which extends through the major part of the hook portion and terminates within the bar.

45. 10. As an article of manufacture, a link for a car coupler positioning device made of metallic bar comprising a shank with a hook at each end forming a journal bearing with each end rounded to form a journal, said bar reinforced by an integral corrugation which extends through the major part of the hook portions and terminates within the bar.

55. 11. As an article of manufacture, a car coupler carrier having a semi-cylindrical projection at each end forming a journal and a semi-cylindrical depression adjacent each end forming a journal bearing.

60. 12. In a railway car; the combination of a car part having a journal and a journal bearing, a coupler carrier having a journal and a journal bearing, and a pair of links swingably suspending the carrier to the car part, one of said links having a journal bearing and a journal at each end engaging 65 the journal and journal bearing respectively

on the car part and the carrier respectively when in normal position.

13. In a railway car; the combination of a car part having a journal and a journal bearing, a coupler carrier having a journal and a journal bearing, and a pair of links swingably suspending the carrier to the car part, one of said links having a journal bearing and a journal at each end engaging the journal and journal bearing respectively 70 on the car part and the carrier respectively when in normal position, the journal of the carrier and the upper journal of the link both moving out of engagement with their respective journal bearings when the carrier 75 swings in one direction and vice versa when the carrier swings in the opposite direction.

14. In a railway car; the combination of a car part having a journal and a journal bearing, a coupler carrier having a journal and a journal bearing, and a pair of links swingably suspending the carrier to the car part, one of said links having a journal bearing and a journal at each end engaging 80 the journal and journal bearing respectively 85 on the car part and the carrier respectively when in normal position, two of said journals moving out of engagement with their journal bearings when the carriage moves 90 in either direction.

15. In a railway car; the combination of a car part element, a coupler carrier element, and links swingably suspending said carrier to said car part, one of said links having a shiftable bearing connection to both of said 95 elements.

16. In a railway car; the combination of a car part element, a coupler carrier element, and a pair of links swingably suspending the opposite ends of the carrier thereto, one of 105 said links having an inwardly projecting hook at one end thereof, the end of the hook forming a journal engageable with a bearing in one of said elements.

17. In a railway car; the combination of 110 a car part element, a coupler carrier element, and a pair of links swingably suspending the opposite ends of the carrier thereto, said links having an inwardly projecting hook at each end thereof, the ends of the hooks 115 forming journals engageable with bearings in the car part and carrier respectively.

18. In a railway car; the combination of a car part element, a coupler carrier element, and a pair of links swingably suspending 120 the opposite ends of the carrier thereto, one of said links having an inwardly projecting hook at one end thereof, the end of the hook forming a journal engageable with a bearing in one of said elements, the inside of said 125 hook forming a bearing engageable with a bearing in one of said elements.

19. In a railway car; the combination of a car part element, a coupler carrier element, and a pair of links swingably suspending 130

the opposite ends of the carrier thereto, said links having an inwardly projecting hook at each end thereof, the ends of the hooks forming journals engageable with bearings 5 in the car part and carrier respectively, the inside of said hooks forming bearings engageable with bearings in the car part and carrier respectively.

20. In a railway car; the combination of 10 a car part, a coupler carrier, and a pair of

links swingably suspending the opposite ends of the carrier thereto, one of the links having an inwardly projecting lateral extension with spaced apart supports for the carrier so positioned that the carrier rests 15 entirely upon one support when the link swings in one direction and entirely upon the other support when the link swings in the other direction.

ARTHUR E. SMALL.
